OSCAR H. DICKE, OF ROCHESTER, NEW YORK, ASSIGNOR TO GENERAL RAILWAY SIGNAL COMPANY, OF ROCHESTER, NEW YORK

SIGNALING SYSTEM FOR RAILROADS

Application filed October 15, 1930. Serial No. 488,899.

This invention relates to track circuits for railway signaling systems.

In the use of track circuits of the usual construction, and particularly in cases where the resistance of the ballast between track rails is extremely variable, it has been found that the track circuits will not function safely under all conditions of weather and ballast. For instance, it is possible that the track relay of a track circuit will not drop upon the entrance of a train under extremely dry or high resistance ballast conditions (low ballast leakage), and that the track relay may assume its deenergized danger position even though there is no train in the block if the ballast leakage is very high, that is, the ballast resistance between track rails is very low.

In view of the foregoing and other important considerations, it is proposed in accordance with the present invention to so arrange the track circuit that the track circuit source and the track relay are located at the same end of the track section, with the track relay of such construction that it will not respond to the track circuit source until the current has been modified by suitable means located at the opposite end of the track circuit. This expedient has been resorted to, among other things, in order to reduce the potential across the track rails of the track circuit to an extremely low value, so that very little, if any, change in the operation of the track circuit is experienced due to variation of the ballast resistance. Furthermore, the current that actually flows through the ballast resistance will be of the original and un-modified kind, so that it will have no effect on the track relay.

Other objects, purposes and characteristic features of the present invention will in part be pointed out hereinafter and will in part be obvious from the accompanying drawings.

In describing the invention in detail reference will be made to the accompanying drawings, in which:—

Fig. 1 shows one embodiment of the present invention in which an alternating current is used as the track circuit source, which current is modified by a rectifier;

Fig. 2 shows a modified construction in which a direct current source is used, which current may be modified by an interrupter to actuate an altering current relay;

Fig. 3 shows a modified form of interrupter for the system illustrated in Fig. 2; and

Fig. 4 shows still another modified form of interrupter.

Structure Fig. 1.

Referring to Fig. 1 of the drawings, the track rails 1 have been shown divided into blocks by insulating joints 2, of which the block I and the adjacent ends of two other blocks H and J only have been shown. Since the apparatus of each of the blocks is the same, the apparatus of one block will only be described, like parts of each block being designated by like reference characters having distinctive exponents. In the particular embodiment of the invention shown in Fig. 1, an alternating current source comprising a transformer T included in series with a three-position direct current polar relay DC, is connected across the track rails 1 of the block, the normal direction of traffic being from left to right as indicated by the arrow. At the exit end of the block I a rectifier R is connected across the track rails through the medium of a pole changer switch PC, so that this rectifier R is poled in the track circuit in one direction so long as the signal S¹ assumes either the clear or caution position, but is poled in the reverse direction when the signal S¹ assumes the stop position. The signal S is of course controlled through the medium of the clear wire cl and the caution wire ca which wires are energized through the medium of polar contacts of the track relay DC, all as well understood by those skilled in the art of railway signaling.

Operation Fig. 1

Under normal conditions, that is when there are no trains in the block I, the track relay DC is held in its normal right hand clear position in response to current supplied by one wave of a certain polarity from each cycle of the alternating current derived from the source A and flowing through the following

circuit:—beginning at the secondary winding of the transformer T, wire 10, winding of the relay DC, wire 11, track rail 1, wire 12, contact 13, wire 14, rectifier R, wires 15 and 16, contact 17 of the pole changer switch PC, wire 18, track rail 1, wire 19 back to the secondary winding of the transformer T. Obviously, if the signal S¹ at the entrance to the block J should be moved to its danger position as by reason of a train in said block, the pole changer PC would assume its dotted position, thereby reversing the rectifier R in the circuit just traced, and thereby causing direct current to flow through the track relay DC in the reverse direction, thus operating this relay DC to its left hand position, effecting opening of the clear circuit cl and closure of the caution circuit ca, and effecting operation of the signal S to the caution position.

Let us now assume that a train moving from left to right moves from the block H into the block I, thereby shunting the rectifier R out of the circuit heretofore traced. With the rectifier R shunted out of the circuit alternating current only will flow through the track relay DC, and since this track relay DC is so constructed as not to respond to alternating current this track relay DC will assume its neutral pendent position, thereby opening both the clear circuit cl and the caution circuit ca and effecting operation of the signal S to its danger stop position.

By reason of the fact that the track relay DC is included in series with the secondary winding of the transformer T the impedance drop due to the impedance of the relay DC will cause the voltage across the track rails 1 to be the difference between the voltage of the transformer T and the impedance drop of the relay DC, so that if the rectifier R is of rather low resistance, for current flow in a particular direction, the potential across the track rails 1 of the block I will be comparatively low for the particular waves of alternating current which readily flow through the rectifier R. In other words, the potential across the track rails is extremely low, and for this reason the flow of current through the ballast is very low, and the operating margin of the track circuit is materially improved in spite of extreme variations in ballast resistance.

Structure Fig. 2

In the arrangement shown in Fig. 2 the track circuit includes the primary winding of transformer TF, the track battery 20 and the interrupter IR in series, an alternating current track relay AC being connected to the secondary winding of the transformer TF. The interrupter IR may be of any suitable construction such as an electromagnet 21 which if energized opens its own energizing circuit at the armature contact 22 (see Fig. 3), similar to the usual door-bell type electro-

magnet, may be an interrupter of the motor operated type including a motor 9 and shown in Fig. 2, or may be an interrupter having a contact 23 operated by an electromagnet 24 which operates in accordance with the frequency of alternating current applied to a transmission line 25 extending along the railway track, as shown in Fig. 4.

Operation Fig. 2

Under normal conditions, that is with the block I¹ unoccupied, the track relay AC will be energized by alternating current derived from the secondary winding of the transformer TF, which alternating current is derived from the pulsating current flowing in primary of the transformer and in the track circuit of the block I¹ and including the track rails 1 and the interrupter IR. Let us now assume that there is a train moving from left to right in the normal direction of traffic from the block H¹ into the block I¹. As soon as this train treads upon the track circuit of the block I¹ the interrupter IR will be shunted out, so that only uniform and substantially constant direct current flows through the primary winding of the transformer TF, as a result of which practically no alternating current flows in the secondary winding and the track relay AC, so that this track relay AC is deenergized, thereby operating the signal S to its stop position. The transformer TF is used primarily for filtering purposes, in that it prevents continuous direct current in the track circuit from energizing the relay AC. For reasons already explained in connection with the embodiment of the invention shown in Fig. 1, the potential across the track rails in Fig. 2 is also extremely low as compared with the potential of the track battery 20, so that the leakage current flowing through the ballast resistance is correspondingly low and the variable effect of this ballast resistance has a correspondingly smaller effect upon the function of the track circuit under consideration, furthermore the current flowing through the ballast is direct continuous current and does not affect the relay AC.

Having thus shown and described several specific embodiments of the present invention, it is desired to be understood that the particular embodiments of the invention illustrated in the drawings have not been selected for the purpose of illustrating the scope of the invention nor have they been selected to show the exact construction preferably employed in practicing the invention, but have been selected to facilitate description of the invention as well as its operating features and characteristics, and it is further desired to be understood that various changes, modifications and additions may be made to adapt the invention to the particular problem encountered in practicing the

same, all without departing from the spirit or scope of the invention or the idea of means underlying the same, except as demanded by the scope of the following claims.

5. What I claim as new is:—

1. In combination, a section of railway track isolated from the remaining track by insulating joints, a track circuit for said section including a source of current of one character and an electro-responsive device responsive only to current of a different character connected in series across the track rails at one end of said section, and means connected across the track rails at the other end 70 of said section for changing the current derived from said source to a current of said different character.
2. In combination, a section of railway track isolated from the remaining track by 20 insulating joints, a track circuit for said section including a source of current of one character and an electro-responsive device responsive only to current of another character connected in series across the track rails at one end of said section, and means connected across the track rails at the other end of said section for changing the current derived from said source to a current of said different character. 80
- 25 3. In combination, a section of railway track isolated from the remaining track by insulating joints, a track circuit for said section including a source of direct current and an electro-responsive device responsive only to pulsating or alternating current connected in series and across the track rails at one end of said section, and means connected across the track rails at the other end of said section for changing said direct current to pulsating current. 90
4. In combination, a section of railway track isolated from the remaining track by insulating joints, a track circuit for said section including a source of alternating current 95 and an electro-responsive device responsive only to direct current connected in series across the track rails at one end of said section, and means connected across the track rails at the other end of said section for changing said alternating current to direct current. 100
5. In combination, a section of railway track isolated from the remaining track by insulating joints, a track circuit for said section including a source of current of one character and an electro-responsive device responsive only to two distinctive currents each of another character connected in series across the track rails at one end of said section, and means connected across the track rails at the other end of said section for changing the current derived from said source to one or the other of said distinctive currents of said another character. 110
6. In combination, a section of railway track isolated from the remaining track by insulating joints, a track circuit for said section including a source of alternating current and an electro-responsive device responsive only to direct current connected in series across the track rails at one end of said section, a rectifier connected across the track rails at the other end of said section for changing said alternating current to uni-directional current, and a contact included in series with said rectifier and controlled in accordance with traffic conditions in advance of said section. 115
7. In combination, a section of railway track isolated from the remaining track by insulating joints, a track circuit for said section including a source of current of one character and an electro-responsive device responsive only to current of a different character connected in series across the track rails at one end of said section, means connected across the track rails at the other end of said section for changing the current derived from said source to a current of said different character, and a contact included in series with said means and controlled in accordance with traffic conditions in advance of said section. 120
8. In combination, a section of railway track isolated from the remaining track by insulating joints, a track circuit for said section including a source of current of one character and an electro-responsive device responsive only to current of another character connected in series across the track rails at one end of said section, means connected across the track rails at the other end of said section for changing the current derived from said source to a current of said another character, and a contact included in series with said means and controlled in accordance with traffic conditions in advance of said section. 125
9. In combination, a section of railway track isolated from the remaining track by insulating joints, a track circuit for said section including a source of alternating current and an electro-responsive device responsive only to direct current connected in series across the track rails at one end of said section, and a rectifier connected across the track rails at the other end of said section for changing said alternating current to uni-directional current. 130
10. In combination, a section of railway track isolated from the remaining track by insulating joints, a track circuit for said section including a source of alternating current and an electro-responsive device responsive only to direct current connected in series across the track rails at one end of said section, a rectifier connected across the track rails at the other end of said section for changing said alternating current to uni-directional current, and a contact included in series with said rectifier and controlled in accordance with traffic conditions in advance of said section.
11. In combination, a section of railway

track isolated from the remaining track by insulating joints, a track circuit for said section including a source of direct current and an electro-responsive device responsive only to pulsating or alternating current connected in series and across the track rails at one end of said section, and a current interrupter connected across the track rails at the other end of said section for changing said direct current to pulsating current and operated by the current flowing in the track rails.

12. In combination, a section of railway track isolated from the remaining track by insulating joints, a track circuit for said section including a source of direct current and an electro-responsive device responsive only to pulsating or alternating current connected in series and across the track rails at one end of said section, and a current interrupter connected across the track rails at the other end of said section for changing said direct current to pulsating current and consisting of an electro-magnet in series with a contact thereof closed when said electro-magnet is deenergized.

13. In combination, a section of railway track isolated from the remaining track by insulating joints, a track circuit for said section including a source of direct current and the one winding of a transformer in series connected across the track rails at one end of said section, a relay connected across the secondary winding of said transformer, and means connected across the track rails at the other end of said section for changing said direct current to pulsating current.

14. In combination, a section of railway track isolated from the remaining track by insulating joints, a track circuit for said section including a source of direct current and an electro-responsive device responsive only to pulsating or alternating current connected in series and across the track rails at one end of said section, and traffic controlled means connected across the track rails at the other end of said section for changing said direct current to pulsating current.

15. In combination, a section of railway track isolated from the remaining track by insulating joints, a track circuit for said section including a source of current of one character and an electro-responsive device responsive only to two distinctive currents each of another character connected in series across the track rails at one end of said section, and means controlled by traffic conditions in advance and connected across the track rails at the other end of said section for changing the current derived from said source to one or the other of said distinctive currents of said another character.

16. In combination, a section of railway track isolated from the remaining track by insulating joints, a track circuit for said section including a source of alternating current

and an electro-responsive device responsive only to direct current of one polarity or the other and connected in series across the track rails at one end of said section, and means controlled in accordance with traffic conditions in advance and connected across the track rails at the other end of said section for changing said alternating current to direct current of one polarity or the other.

In testimony whereof I affix my signature.

OSCAR H. DICKE.
